END CONNECTION FOR WRIST WATCH STRAPS AND BRACELETS

William Joseph Pfeifer, Point Pleasant, N. J., assignor to Forstner Chain Corporation, a corporation of New Jersey

Application May 27, 1948, Serial No. 29,581

6 Claims. (Cl. 24—265)

1

The present invention relates to the jewelry art, and has particular reference to improvements in end connections for wrist watch straps and bracelets.

The principal object of the invention is to provide an end connection having a housing and a movable cover plate therefor, the parts being mounted so that both a swinging and a sliding movement of the cover plate relative to the housing is required for opening and closing movement of the end connection parts.

An additional object of the invention is to provide an end connection which includes a housing slidably mounted on the strap end, and a cover element which is secured to the strap end and releasably engages the housing to lock a received watch bail therein.

Another object of the invention is to provide a snap lock cover plate for an end connection housing which utilizes pull or tension of the strap parts to retain the cover plate in closed relation to the housing.

A further object of the invention is to provide an end connection adapted to receive a watch bail or the like and a cooperating cover for the housing which is hinged to the strap end and releasably interlocks with the housing.

With the above and other objects and advantageous features in view, the invention consists of a novel arrangement of parts more fully disclosed in the detailed description following, in conjunction with the accompanying drawings and more specifically defined in the claims appended thereto.

In the drawings,

Fig. 1 is a perspective view of a wrist watch strap equipped with illustrative end connections embodying the invention;

Fig. 2 is a top plan view of Fig. 1;

Fig. 3 is a detail sectional view on the line 3—3 of Fig. 2, the end connection parts being in closed relation;

Fig. 4 is a view similar to Fig. 3, the parts being shown in open relation;

Fig. 5 is an enlarged perspective view of the end connector parts in closed relation; and

Fig. 6 is an enlarged exploded view showing the individual parts of Fig. 5.

It has been found desirable to provide an end connection for a wrist watch strap or bracelet, which includes a housing adapted to slidably seat on the strap end and which has a watch bail receiving recess, and a cover or lock plate which is secured to the strap end, preferably by means of a hinge connection, and which releasably inter-

2

locks with the housing to cover the recess and lock the watch bail therein. To this end I provide a housing which has a hollow body through which the strap end extends, and which has a forwardly extending tongue shaped in hook form to provide a watch bail receiving recess; and I provide a cover plate which extends into the hollow body and is hinged to the strap end and is adapted to snap lock with the housing tongue when the cover plate moves back into the hollow body.

Referring to the drawings, the wrist watch strap 10 is detachably connected to a watch or ornament 11 by end connections 12, a preferred 15 design for the end connections and their parts being shown in Figs. 5 and 6.

The illustrated end connection 12 is preferably made of resilient metal and includes a housing 13 having a hollow body 14 with a bottom 15, sides 16, 17, and a top 18, the sides curving as illustrated to merge with the bottom and the bottom having a resilient tongue 19 which widens laterally and extends upwardly and has a rearwardly directed terminal lip 20, whereby a recess 21 is 25 formed to receive a watch bail 22 or the like, see Fig. 3.

The end 23 of the wrist watch strap has a hinge plate 24 secured thereto, as by a rivet or rivets 25 which passes through aligned openings 30 in the strap end and the hinge plate. The hinge plate 24 has spaced hinge rolls 26, and a cover plate 27 has a hinge roll 28 adapted to seat intermediate the hinge rolls 26 and to be hinged thereto by means of a hinge pin 29. The cover plate 27 has inclined sides 30, 31 which are narrow at the hinge end and extend into the housing body, a slot 32 being provided at each housing side to act as a guide, and the cover plate widens at the outer end to provide a snap edge 33 adapted to snap below the tongue lip 20, the end of the cover plate having a vertical extension 34 and a horizontal extension 35 which cooperate with the snap edge 33 to form a recess 36 for receiving the tongue lip 20; the extension 35 covers the tongue lip 20 when in closed relation.

With the parts assembled and closed as shown in Fig. 5, the cover plate may be pulled up enough to release the snap edge 33 from the under side of the tongue lip 20, and then swung to open the housing recess 21 as shown in Fig. 4, this swinging movement against the front edge of the housing body pulling the strap end forwardly. When the watch bail is inserted in the 55 housing recess the cover plate may be snapped

down, see Fig. 3, the closing movement snapping the edge 33 below the tongue lip which seats in the recess 36; at the same time the cover plate slides back into the body of the housing through the guide slots 32.

It is thus clear that the locking movement combines a snap lock with a relative sliding movement of the cover plate which firmly locks the parts in closed position; the cover plate is firmly held at its forward end and seats in the guide slots at its rear end to be firmly held in the hollow body against swinging movement. Inadvertent opening of the parts is prevented, as opening requires a forward movement of the cover plate against the tension or pull of the 15 wrist watch strap as well as a turning movement of the cover plate.

Although I have described a specific constructional embodiment of the invention, such changes in the size, shape, and arrangement of the parts may be made as are desirable for different wrist watch strap and bracelet designs, within the spirit and the scope of the invention as defined in the appended claims.

I claim:

1. An end connection for a wrist watch strap or the like, comprising a housing having a hollow body, a forwardly extending element forming a recess, said element having a terminal lip, a hinge plate movably positioned in the hollow body and adapted to be connected to a bracelet end extending into the hollow body, and a cover plate having its rear end hinged to the hinge plate and its forward end provided with a snap edge adapted to releasably snap past the housing element terminal lip, the sides of the hollow body having guide slots for receiving the rear end of the cover plate.

2. An end connection for a wrist watch strap or the like, comprising a housing having a hollow body with a top, sides and bottom, an extension on said bottom forming a tongue spaced from the body to provide a recess therebetween, said tongue having a terminal lip, and a cover plate with tapered sides, the narrow end of said cover plate extending into the hollow body, a hinge plate in said hollow body hinged to the cover plate, the wide end of said cover plate having a snap edge adapted to releasably snap past the housing tongue terminal lip.

3. An end connection for a wrist watch strap or the like, comprising a housing having a hollow body with a top, sides and bottom, an extension on said bottom forming a tongue spaced from the body to provide a recess therebetween, said tongue having a terminal lip, and a cover plate with tapered sides, the narrow end of said cover plate extending into the hollow body, a hinge plate in said hollow body hinged to the cover plate, the wide end of said cover plate having a snap edge adapted to releasably snap past

the housing tongue terminal lip, the sides of the hollow body having guide parts slidably engaging the narrow end of the cover plate.

4. An end connection for a wrist watch strap or the like, comprising a housing having a hollow body with a top, sides and bottom, an extension on said bottom forming a tongue spaced from the body to provide a recess therebetween, said tongue having a terminal lip, and a cover plate with tapered sides, the narrow end of said cover plate extending into the hollow body, a hinge plate in said hollow body hinged to the cover plate, the wide end of said cover plate having a snap edge adapted to releasably snap past the housing tongue terminal lip, the sides of the hollow body having guide slots slidably engaging the narrow end of the cover plate.

5. An end connection for a wrist watch strap or the like, comprising a housing having a hollow body with a top, sides and bottom, an extension on said bottom forming a tongue spaced from the body to provide a recess therebetween, said tongue having a terminal lip, and a cover plate with tapered sides, the narrow end of said cover plate extending into the hollow body, a hinge plate in said hollow body hinged to the cover plate, the wide end of said cover plate having a snap edge adapted to releasably snap past the housing tongue terminal lip.

6. An end connection for a wrist watch strap or the like, comprising a housing having a hollow body with a top, sides and bottom, an extension on said bottom forming a tongue spaced from the body to provide a recess therebetween, said tongue having a terminal lip, and a cover plate with tapered sides, the narrow end of said cover plate extending into the hollow body and adapted to be hingedly connected to a strap or bracelet end, and the wide end of said cover plate having a recess to receive the housing tongue terminal lip and a snap edge adapted to releasably snap past the housing tongue terminal lip, the sides of the hollow body having guide slots slidably engaging the narrow end of the cover plate.
